EDWIN C. HAGEMANN, OF SHORT HILLS, NEW JERSEY, ASSIGNOR TO WESTERN ELECTRIC COMPANY, INCORPORATED, OF NEW YORK, N. Y., A CORPORATION OF NEW YORK

TOROIDAL INDUCTANCE DEVICE

Application filed March 1, 1930. Serial No. 432,359.

This invention relates to the manufacture of inductance devices and more especially to the manufacture of non-magnetic cores on which the inductance devices are wound and 5 non-magnetic core shells employed between magnetic cores and the windings thereon.

An object of the invention is to provide cores or forms having integral spacers for separating the inductance devices wound 10 thereon.

Another object of the invention is to provide molded toroidal core shells having integral spacers for separating the inductance devices wound thereon.

15 According to one feature of the invention, a toroidal core having an H-shaped cross section, around which the windings are applied, and having spacers for definitely and accurately locating the individual windings on 20 the core, is molded in a suitable mold with any desirable molding material. Preferably the entire core, including the integral spacers are made of phenolic condensation products.

25 According to another feature of the invention, a toroidal core shell is formed of any desirable insulating material to fit around the magnetic core and to insulate the windings from the magnetic core. Spacers formed 30 integral with the core shell are provided to definitely and accurately locate the individual windings on the core.

The invention will be more fully understood from the following disclosure and accompanying drawing, in which:

35 Fig. 1 is a perspective view of an H-shaped core with integral spacers;

Fig. 2 is a section taken on the line 11—11, Fig. 1;

40 Fig. 3 is a perspective view of the form of core shell with integral spacers thereon, the core shell being molded in one piece around the magnetic core;

45 Figs. 4 to 6 inclusive show different methods of forming or molding the core shell in parts so that the parts can be readily assembled over the cores to form a complete cover or shell;

50 Fig. 7 is a perspective view of a core shell

formed from layers of insulating material such as paper; and

Fig. 8 shows a preferred method of building up the paper layers to form the core shell parts shown in Fig. 7.

55 Referring to Figs. 1 and 2, the toroidal core or winding form 20 is formed or molded of insulating material of any suitable kind such as phenol plastic or the like. The core 20 is preferably constructed so as to have a cross section of H shape as shown in Fig. 2. Such a cross section makes it possible to readily mold the core and the integral spacers with a relatively small amount of 60 molding material. A U shape could also be used. Four spacers 21, 22, 23 and 24, preferably of the same material as the core 20, are molded integral with the core to form four winding space sections 25, 26, 27 and 28. The inductance devices are wound on 65 the core 20 in each of the winding sections 25, 26, 27 and 28. When only two sections are required, the spacers 22 and 24 can be omitted.

70 Referring to Fig. 3, a cover or shell 30 is molded or formed around the toroidal magnetic core sections 31, 32 and 33 to form an insulating cover or shell over the core laminations 31, 32 and 33. The winding is applied over the shell. The shell 30 may be 75 molded or formed of any suitable insulating material such as phenol plastic and the like. Four spacers 34, 35, 36 and 37 are formed or molded integral with the shell 30, to provide 80 four winding space sections. Additional spacers can be provided or fewer used than the number shown, depending upon the number of winding spaces desired.

85 Fig. 4 is a molded shell part 40 which comprises half of a complete cover or shell. On each shell part 40 is molded or formed integral therewith half of each of the desired spacers 42, 43, 44 and 45. Two core shell parts 40 and the one or more magnetic core 90 laminations such as 31, 32 and 33 in Fig. 3 are assembled into a unit which will be similar to the unit assembly shown in Fig. 3.

95 Figs. 5 and 6 show a molding shell part 46 which comprises half of the shell part 40 100

shown in Fig. 4. Four such shell parts 46 are assembled over the magnetic core sections to form the complete core and shell assembly such as shown in Fig. 3. The division 5 between the shell parts 46 is preferably made as shown so that the line of division will not be parallel with the turns of the windings wound thereon.

Fig. 7 shows a formed shell or cover for 10 the magnetic core laminations 31, 32 and 33 formed from shell parts 50. The shell parts 50 are preferably made up of layers of insulating material such as paper, which is preferably impregnated with suitable insulating material.

Fig. 8 shows a preferred method of constructing the shell parts 50 of layers of insulating material 56, on each end of which are projections 51, 52 and 53. Preferably 20 V-shaped slots 54 are cut in the outer edge and cuts 55 are made in the inner edge of each of the sheets or layers of insulating material in order to facilitate forming the shell parts 50. Preferably the V-shaped slots 54 and the 25 cuts 55 are located as shown in Fig. 8 in each of the insulating layers or sheets so that they will not fall directly over the V-shaped slots and cuts in the layers of insulating material directly above and below. The individual 30 layers 56 are held together after the forming operation, preferably by means of an adhesive of satisfactory electrical characteristics. The projections 51, 52 and 53 are bent or folded back at right angles to the core cover 35 to form the integral spacers. Four of the shell parts 50 are assembled over the magnetic core sections to form the complete cover or shell. Preferably the abutting projections 51, 52 and 53 on the adjacent shell parts 50 40 are fastened together by means of an adhesive in order to strengthen the integral spacers which they form. When four winding sections of equal size are desired instead of the two winding sections shown in Fig. 45 7 the shell parts are constructed to form a 90° angle instead of a 180° angle. Preferably there will then be projections 51, 52 and 53 on each end of the 90° section of the shell part.

Heretofore it has been found difficult to attach spacers securely and accurately to core forms or shells and to hold them in this manner under commercial winding speeds, particularly with the ever increasing rate of winding speeds procurable with semi-automatic or full-automatic winding processes. In wooden core forms it has been found a costly operation to position the spacers securely and accurately, as is required for uniformity of product. This is especially true 55 where a high degree of magnetic and capacity balance is required between different parts of a coil, as in the case of certain loading coils, or repeating coils for example where low crosstalk and small longitudinal unbalance is required. The molded, pressed or

otherwise formed core or shell of the present invention can be made cheaply and accurately, and results in a uniform product and less rejections due to winding sections collapsing or partially collapsing.

It is to be understood that the invention is not to be limited to the particular embodiments shown, nor to the specific arrangements that have been described and shown in detail, but only by the scope of the appended claims.

What is claimed is:

1. A new article of manufacture comprising an annular member adapted for winding a plurality of inductance devices thereon and having a plurality of spacers of non-magnetic material formed integral with said annular member dividing the winding space on said annular member into a plurality of sections of predetermined size.

2. A new article of manufacture comprising an annular member adapted for winding a plurality of inductance devices thereon and having a plurality of spacers of non-magnetic material formed integral with said annular member dividing the winding space on said annular member into a plurality of sections of predetermined size, said annular member having a cross sectional area less than the annular space enclosed by the windings thereon.

3. A new article of manufacture comprising an annular H-shaped molded member adapted for winding a plurality of inductance devices thereon and having a plurality of integral spacers dividing the winding space on said annular molded member into a plurality of sections of predetermined size.

4. A toroidal core for inductance devices comprising an annular H-shaped molded member of non-magnetic material and a plurality of non-magnetic spacers molded integral with said core and adapted to divide the winding space on said core into a plurality of sections of predetermined size.

5. A toroidal core for inductance devices comprising an annular H-shaped molded member of non-magnetic material and a plurality of non-magnetic spacers molded integral with said core and adapted to divide the winding space on said core into a plurality of sections.

6. An annular shaped structure of insulating material adapted to receive a coil winding of a plurality of sections, said insulating material being formed to provide integral spacers for separating the different winding sections.

In witness whereof, I hereunto subscribe my name this 24th day of February, 1930.

EDWIN C. HAGEMANN.
